AMPLIFIER FOR UNDERWATER
LISTENING APPARATUS

Frank P. Herrnfeld, Los Angeles, Calif., assignor
to the United States of America as represented
by the Secretary of the Navy

Application January 5, 1946, Serial No. 639,456

1 Claim. (Cl. 177—386)

1

This invention relates in general to audio amplifiers and more particularly to audio amplifiers used with listening gear for submarines and surface craft.

In general, the amplifier of this invention is operated with a signal from a magnetostriction hydrophone and the amplifier output is supplied to a pair of headphones. The hydrophone is mounted to be oriented through an angle of 360° by remote means which are indicative of the direction of the hydrophone. When used with a baffle the hydrophone has very directional characteristics. Hence, the operator may turn the hydrophone to a point where the signal is a maximum in the headphones, and the resulting bearing of the hydrophone will be the bearing of the source of signals.

If the listening gear is mounted on a surface ship, it may be used for the detection of submarines, either submerged or afloat, or the approach of other surface ships at night or in a fog. The listening gear is usually mounted on submarines for the same purpose, and it becomes a very important piece of apparatus when the submarine is submerged, serving more or less as the eyes of the submarine.

Various problems arise in the development of the apparatus of this invention, for instance certain underwater noises are known to have certain frequencies, and for this reason a multi-band filter is required in the amplifier.

Oftentimes it is desirable to know if the signals contain supersonic frequencies. In order to obtain this information a supersonic detector must be included in the amplifier.

When magnetostrictive hydrophones are used requiring magnetizing at certain intervals, a magnetizer is included in the amplifier.

To supplement the head phones, provision is usually made for a loudspeaker. In certain cases where the maximum signal output is critical, such as in bearing determination, an electron-ray indicator or a vacuum-tube voltmeter is included in the amplifier circuit.

This invention consists in providing an amplifier capable of producing optimum operation of standard listening gear apparatus. Accordingly an object of this invention is to provide an amplifier capable of receiving underwater signals from a hydrophone, amplifying and treating said signals until they become intelligible to the operator.

Another object is to provide an amplifier that indicates the signal audibly by headphone and

2

loudspeaker, and visually by an electron ray or vacuum tube voltmeter indicating device.

Another object is to provide an amplifier that is capable of magnetizing the hydrophone at intervals where such magnetization is required by the hydrophone.

Another object is to provide an amplifier that is capable of selectively indicating the presence of supersonic frequencies.

Another object is the provision of an amplifier system which will be economical to manufacture, reliable in operation and which possesses all of the qualities of ruggedness and dependability in service.

Figure 1 is a block diagram of the apparatus of this invention.

Figure 2 is a detail circuit diagram of the amplifier of this invention.

Referring to Figure 1, the hydrophone 1 may be of any type, though for the purposes of this invention a magnetostrictive hydrophone is preferred. The structure of the hydrophone is such that the responsive unit has the shape of a long cylinder, which when semi-encased in a baffle has a marked directional response characteristic. The hydrophone may be constructed in two sections so that the windings may be series connected either aiding or opposing.

Preamplifier 2 may be a simple three-stage amplifier; or a two-stage, resistance-coupled amplifier; or a three-stage, resistance coupled, negative - feedback - stabilized amplifier. The latter is the preferred form.

The filter network 3 may have the following frequency bands, 1—flat, 2—500 cycle high pass, 3—1500 cycle high pass, 4—3000 cycle high pass, and 5—5500 cycle high pass.

It may have the following combination, 1—flat, 2—600 cycle high pass, 3—1200 cycle high pass, and 4—2400 cycle high pass.

It also may have the following combination, 1—bass boost, 2—flat, 3—500 cycle high pass, 4—3000 cycle high pass, and 5—6000 cycle high pass.

It also may have the following combination, 1—bass boost, 2—2000 cycle low pass, 3—flat, 4—500 cycle high pass, 5—3000 cycle high pass, and 6—6000 cycle high pass.

Or it may have the following combination, 1—bass boost, 2—2000 cycle low pass, 3—flat, 4—500 cycle high pass, 5—1500 cycle high pass, and 6—4500 cycle high pass.

It is obvious that various combinations of bands may be used. While they cover approximately the same bands, the exact figures may vary some-

what due to the particular design of the remainder of the apparatus.

The final amplifier may be a single tube, or it may be a three-stage amplifier for the operation of a loudspeaker. In a preferred form it is a two-stage amplifier with one tube working singly and two tubes working as a push-pull stage in the output. The conversion from single to push-pull stage is accomplished by phase inversion. A small fraction of the output voltage is fed back to the cathode of the first stage of the two-stage amplifier to reduce harmonics and to stabilize the amplifier against variations in plate supply voltage. A diode may be connected, through a switch, to the control grid of one of the push-pull tubes. It is used as a rectifier, making it possible to detect supersonic signals which would otherwise go unnoticed by the listener. This two-stage amplifier may also be made into a three-stage amplifier by adding another tube working singly, and the tubes may be resistance-capacity coupled. The preamplifier and the final amplifier are designed for either D. C. or A. C. operation, the choice depending upon the type of power supply available.

The output of the final amplifier may operate one or more indicating devices. It has already been pointed out that headphones 6 and/or loudspeakers 6 may be used as indicators and that supersonic detection 8 is added to the amplifier to render it more useful for the purpose specified.

Another type of indicator frequently used is the electron-ray indicator 7 and/or the electron voltmeter. These indicators are generally utilized when the apparatus is used for bearing determination, because a more accurate indication of the maximum signal is possible with these indicators than with those of the aural type. The electron ray indicator is operated from the output of a high pass filter for greater accuracy at high frequencies.

When the magnetostrictive hydrophone is used, it is desirable to send a magnetizing current through it at intervals for magnetization purposes. This is accomplished by switching condensers, that are maintained charged from the output of the final amplifier, to discharge through the hydrophone. This discharge of the condensers through the hydrophone remagnetizes the transducer as desired. The condensers also have a desirable filtering effect on the final amplifier, that is the reason they are charged from the output circuit. The switch and condensers are generally designated the magnetizer 9 in Figure 1.

The amplifier circuit disclosed in Figure 2 was designed for use with the topside-mounted listening gear for submarines and the through-the-hull-mounted listening equipment for surface ships. In general, this amplifier is operated with a signal from a straight magnetostriction hydrophone and its output is supplied to a pair of headphones. Because of its use with the above mentioned hydrophone, facilities are provided to remagnetize the hydrophone by discharging a bank of condensers through it. This amplifier is capable of handling signals as low in intensity as the resistance noise on the input. The amplifier features negative feedback and a simple, but effective, selective filter circuit having five positions and employing only one coil. The gain is automatically increased as the filters are inserted in order to keep the intensity of the sound approximately constant. The maximum power gain at 1000 cycles with the filter switch in the "flat" position is 104 db. An electron-ray indicator tube

is provided on the panel as an aid in training the hydrophone and it is operated at all times through a 5500 cycle high-pass filter. This filter is used because the hydrophone has its best directive characteristics at high frequencies.

The amplifier of Figure 2 has five stages of amplification. It has an input transformer T-101 with a nominal impedance ratio rating of 50 to 100,000 ohms. The input transformer feeds a two-stage, resistance-coupled, negative feedback stabilized amplifier consisting of vacuum tubes V-101 and V-102. This amplifier feeds the audio frequency filter assembly directly.

The filter assembly consists of impedance matching and loss adjusting networks followed by appropriate filters. The various networks are connected to the circuit by means of a multipole, multiposition switch S-104. There are five switch positions, as follows: (1) bass boost, (2) flat, (3) 500 cycle high pass, (4) 3000 cycle high pass, and (5) 6000 cycle high pass. Step 1 gives the amplifier a peak gain of 122 db. at about 80 cycles, dropping off above 160 cycles at a rate of approximately 6 db. per octave. Step 2 gives the amplifier a "flat" frequency response with a maximum gain of 105 db. at 1000 cycles. Step 3 gives the amplifier characteristics approximately inverse of step 1, having a maximum gain of 108.5 db. at 9000 cycles, and dropping off below 1500 cycles at the rate of 5 db. per octave. Step 4 has a maximum gain 114 db. at 8500 cycles with a low frequency cutoff of 18 db. per octave below 3000 cycles. Step 5 has a maximum gain of 119 db. at 8500 cycles with a low frequency cut off at 6000 cycles.

The filter is terminated in a continuously variable, tapered volume control consisting of a potentiometer R-156 shunted by a resistor R-150. This is followed by a three stage amplifier using vacuum tubes V-103 and V-105 working singly, and V-107 and V-108 working as a push-pull stage in the output. The conversion from single to push-pull stage is accomplished by a phase inversion. A small fraction of the output voltage is fed back to the cathode of the second stage (V-106) of the three-stage amplifier to reduce harmonics and to stabilize the amplifier against variations in plate supply voltage.

There are several reasons for using a push-pull stage in the output. Since the amplifier of the particular circuit illustrated in Figure 2 has to work from a power supply varying from 80 to 130 volts D. C., a voltage amplifier triode or pentode would not give sufficient power output to drive two low impedance type headphones with sufficient volume. In order to keep the cost at a minimum and to get enough power output for dual headphone operation, the push pull circuit seemed the best solution. The use of a power pentode, if a 0.3 ampere, 6 volt tube were available, would require an output transformer capable of carrying a D. C. plate current of 15 to 20 ma.

A strapping block in the output gives the user the choice of operating either low or high impedance headphones. When two low impedance phones are used, a small mismatch for the output tube occurs, increasing the harmonic content slightly when full output from the amplifier is demanded. It is not often that the full output is required.

The electron ray indicator tube V-104, preceded by a voltage amplifier V-109, a high pass filter with a 6000 cycle cut off, a half wave rectifier (one half of V-105) and an RC filter, is fed from the output of the push pull power stage through a volume control R-157. As most of

the energy received by the amplifier lies below 6000 cycles, a stage of voltage amplification had to be added to get sufficient sensitivity to operate the electron ray indicator without excessive loudness in the headphones.

The other diode of V-105 is connected through a switch to the control grid of one of the push pull tubes and is used as a rectifier, thus making it possible to detect supersonic signals which would otherwise go unnoticed by the listener. The connection of V-105 to the voltage supply through C-119 and R-137, and by way of switch S-102 to the grid of V-107, provides a selective rectifier for high frequency signals which can pass through C-119. Since they only pass through V-105, a rectifier tube, in one direction, the result is to alter the bias on the tube V-107, thereby causing the sonic signals impressed on the grid to be changed in intensity as heard at the phones, use being made of the non-linear characteristic of the push-pull tubes. The rectifier action is ineffective with sonic frequency signals and effective for frequencies of much higher value. Thus closing switch S-102 causes a variation in the signal intensity.

Provision is made for remagnetizing the hydrophone when necessary, and this is accomplished by discharging a bank of condensers through the winding of the hydrophone. The magnetizer is a condenser-discharge device consisting of four 40 mfd. electrolytic condensers C-133 to C-134 in parallel, which discharge their energy through a key K-101 into the hydrophone when its cable is plugged into the magnetizer input jack J-102. With the magnetizer key in the unoperated position, the condensers serve as part of the filter circuit in the push pull output stage. The filter circuit for the push-pull stage is seen by tracing the power circuit from switch S-101 to resistance R-146, to normally closed contacts of switch K-101, and to condensers C-133 and C-134, opposite terminals of which are grounded. The ungrounded connection to the condensers and R-146 leads to the screen grids of V-107 and 108, and to the plates of V-107 and V-108 by way of the center tap 4 and end connections 3 and 5 of T-102. The capacitance-resistance combination in the normally unoperated condition of switch K-101 and the inductive coils of the primary of T-102, act as an effective power or noise filter.

In operation, the jack J-101 is plugged into the hydrophone output. The signal passes through transformer T-101 and is amplified in preamplifier V-101 and V-102. The operator selects the filter band by adjusting switch S-104 for optimum operation. The signal coming from the filter is amplified in amplifier V-103, V-106, V-107 and V-108 and fed to high impedance headphones through jack J-103. If it is desirable to use low impedance headphones they are fed through jack J-104 and transformer T-102.

The operator now has the apparatus in operating condition and can proceed with the scanning, which he accomplished by orienting the hydrophone through 360°. If a signal suggestive of the noise of a vessel is received, the filter bands may be readjusted to determine the predominant frequencies. A bearing of the signal may be secured by orienting the hydrophone until the signal strength is a maximum in the headphones and reading the bearing of the hydrophone. However, this method may be improved upon by turning on electron ray V-104, and since the electron ray operates on the higher frequencies and the hydrophone is more sensitive to direction at the higher frequencies, the orienting can be made by the pattern of the electron ray more accurately than by ear.

Assuming that a vessel has been detected, it may be desirable to know whether or not the said vessel is searching with echo ranging and detecting equipment. This can be determined by throwing detector switch S-102 which renders audible in the headphones any supersonic frequencies present.

Hydrophones require magnetizing at intervals. This may be accomplished by connecting the magnetizer input J-102 to the hydrophone input J-101 and closing key K-101. When this is done the filter condensers in the push pull output circuit are discharged through the hydrophone for magnetizing purposes.

What is claimed is:

In an amplifier for underwater listening apparatus, a preamplifier stage receiving the input from the hydrophone and delivering the output to a selective band filter, a selective band filter, a final amplifier stage receiving the input from said filter and delivering the output to utilization apparatus, a noise filter in the output circuit of said final amplifier including normally charged condensers, means including a coil surrounding said hydrophone and connected through a switch to said condensers for supplying at will a magnetizing current for the hydrophone, an electron-ray device connected to the output circuit of said final amplifier for bearing determination purposes and a detector connected to the input circuit of the last stage of the final amplifier to render audible in the utilization apparatus any supersonic frequencies present.
